Primary Examiner — Jack Reickel*Assistant Examiner* — John M Otte(74) *Attorney, Agent, or Firm* — Leanne Taveggia Farrell; Westman, Champlin & Koehler, P.A.**CLAIM**

The ornamental design for a mobile communication terminal with graphical user interface, as shown and described.

DESCRIPTION

The sole FIGURE is a front elevation view of an embodiment of a mobile communication terminal with graphical user interface.

The broken lines shown in the drawings of a mobile communication terminal and certain graphic features of the graphical user interface form no part of the claimed design.

1 Claim, 1 Drawing Sheet(56)
